UNIVERSAL GRINDING FIXTURE

Adolf L. Meyer, Santa Clara County, Calif.

Application March 21, 1950, Serial No. 150,931

2 Claims. (Cl. 51—218)

1

The present invention relates to grinding fixtures and the like and is concerned more particularly with a device of the above character which is especially constructed for the sharpening of the cutting flutes or teeth of end mills, reamers, taps, and the like, as well as for other sharpening operations on tools, such as threading tools and Carbolyt tool bits.

In general, it is the object of the present invention to provide a universal cutting tool holder by means of which any angle and clearance can be correctly and quickly obtained together with fast accurate indexing of the various flutes to grinding position. The fixture is also useful in various other types of machine operations as a work holder, for example, in producing eccentric pins, in drilling angular holes, in grinding annular end and side surfaces, and various other machining operations.

The above and other objects of the invention will be apparent from the following description of a preferred embodiment of the invention, as illustrated in the accompanying drawings, in which:

Figure 1 is a plan view of the fixture as it would be installed in place on the work plate of a surface grinder with the grinding wheel indicated at one side for a clear view of the fixture.

Figure 2 is a side elevational view of the fixture showing its relation to a surface grinder and with an end mill in position for sharpening.

Figure 3 is a vertical sectional view taken as indicated by the line 3—3 in Figure 2.

Figure 4 is a fragmentary longitudinal sectional view taken as indicated by the line 4—4 in Figure 1.

Figure 5 is an enlarged plan view of the work holding portion of the fixture showing the various angular graduations.

Figure 6 is a view illustrating the use of the tool in conjunction with sharpening of a thread cutting tool.

Figure 7 is a side elevational view of the adapter employed to hold a thread cutting tool.

Figure 8 is a view of the fixture in place in conjunction with a drill press illustrating the operation of drilling angular holes.

Figure 9 is a diagrammatic view of a modification of the fixture employing a motor drive for turning the work held therein.

Figure 10 is an elevational view of the fixture with a special base plate adapted for mounting on a lathe.

Figure 11 is a fragmentary side elevational

view, partially in section, illustrating the mounting of the fixture on a lathe.

The usual method of sharpening tools having end cutting edges consisting of a plurality of flutes by the use of conventional equipment is a very laborious process and becomes so costly with small sized tools of this character that it is less expensive to buy a new end mill or tap rather than to regrind the cutting edges of a worn one. This is true because the grinding of each flute requires an individual setup operation of the flute with respect to the grinding wheel. In accordance with the instant invention, the work holding fixture is designed for simple easy setup with sight alignment of the tool to be sharpened with respect to the fixture so that multi-fluted end cutting tools can be sharpened in a matter of seconds and with only a first initial setup required. The grinding can be done with the face of an ordinary surface grinding wheel which can be of large diameter and therefore easier to dress and keep sharp and less subject to wear.

Referring to Figures 1 through 5, the universal grinding fixture or cutting tool holder comprises a base member 10 which is of generally rectangular contour and is provided with a flat bottom surface 11 for positioning against the work table 12, for example, of a conventional surface grinder having a disc type grinding wheel 13. The base member 10 is provided with an elongated recessed slot 14 to receive a key 16 associated with a clamping bolt 17 of the usual type employed in securing work on the work table 12. Adjacent one end the base member 10 is provided with an upstanding annular boss 18 which projects outwardly from the end of the base member 10 and is provided with an annular flange 19 about a central aperture 21. The plane of the face of the flange 19 is at exact right angles to the bottom surface 11 of the base member.

The annular boss 18 is a mounting boss for a body member 26 having an apertured boss 27 journaled about the boss 18 and releasably secured thereto by means of a cap screw 28. The tapered end of the boss 27 is provided with opposite sets of graduations 24 extending in both directions from a central "zero" index which cooperates with an index mark 30 on the boss 18 of the base member.

The body member 26 is provided with a second annular boss 31 which has its axis at right angles to the axis of the boss 27. The bore of the boss 31 (Figure 3) is enlarged at 32 adjacent one

end surface 33 having four equally spaced graduations or index marks 34. The boss 31 provides a journalled mounting for a collet-holding quill 36 having a central tapered groove 37 for receiving the complementary end of a clamping cap screw 38 threaded into the boss 31. The quill 36 is provided at its upper end with an annular flange 41 engaging within the recess 32 and forming a seat for an index collar 42 having a frusto-conical outer surface and a lip 42a overlying the edge of the flange 41 and abutting the end surface 33. The quill 36 is shaped interiorly to receive a collet 46 of conventional construction having a keyed connection at 47 with the quill 36 and having associated therewith a suitable clamping nut 48 and a washer 49.

The frusto-conical surface of the collar 42 (Figure 5) is provided with a plurality of series of indexing graduations to permit the quick indexing from flute to flute of any tool having from two to eight, ten or twelve flutes according to the numerals positioned adjacent the respective marks. Other desired index graduations may be provided. The "zero" index mark at 51 has adjacent thereto a clamping set screw 52 by means of which the indexing collar 42 can be connected securely to the quill 36 once the desired "zero" setting of the graduations is desired.

The operation of the fixture in connection with the grinding of a double fluted end mill where central clearance is desired between the flutes will now be described. The fixture is secured in place on the work table 12 (as shown in Figures 1 and 2) and the tool or cutter to be sharpened is placed within the collet 46 and securely clamped therein. It will be noted that with the construction as shown herein the cutting tool being sharpened can be clamped as closely adjacent the cutting teeth as may be desired so that no warped or bent condition of its shank will have any effect on the producing of a true cutting edge on each of the flutes of the tool. With the cutter in place, the body member 26 is rotated on the base member 10 setting the angular graduation 24 desired in alignment with the index mark 30 so that the desired angle of grinding will obtain. Then the flute of the tool to be sharpened is lined up by an indicator or by eye to the desired angular position with respect to the grinding wheel by rotating the sleeve 36 within its boss 31, and the cap screw 38 is tightened to set the tool securely in position as desired. Then the indexing collar 42 is adjusted until its "zero" graduation corresponds with a selected graduation 34 on the body member 26 and the set screw 52 is tightened to set this zero positioning into the machine. The flute aligned with the grinding wheel 13 is then sharpened. Thereafter the cap screw 38 is loosened and, in this case, the quill 36 is turned 180° and is clamped at the 180° position by the clamping screw 38. Then another pass of tool beneath the grinding wheel grinds the other cutting edge in exactly the same manner in which the first cutting edge was ground. The operation with tools having different numbers of flutes will be the same except that a selected group of index marks on the indexing collar 42 are used in accordance with the number of flutes of the cutting tool. For the grinding of center clearance, as shown in the double fluted end mill in Figures 1 and 2, the procedure and operations are exactly the same as described above except that

a different angular setting of the body member 26 on the base member 10 is selected.

For the sharpening of both Acme and U. S. standard thread cutting tools, a bit adapter 56, as illustrated in Figures 6 and 7, is used. The adapter 56 has a cylindrical extension 57 for positioning in a collet 46 having the proper diameter opening to receive it. The body of the adapter 56 is provided with an angularly positioned transverse groove 58, for example, at an angle of 29° as employed in some thread cutting tools, with a plurality of set screws 59 provided in a wall thereof to engage the thread cutting tool 61. The adapter 56 is also provided with a second bit receiving groove 58a which extends in the same general direction as the first groove 58 and is exactly at right angles to the axis of the shaft extension 57. The second groove 58a is also provided with set screws 59 in a wall thereof. With the thread cutting tool in the second groove 58a, its top surface can be readily ground. In Figure 6, the adapter 56 is shown in dotted lines at an angular setting for grinding the desired clearance on a side face of the thread cutting tool.

It will be appreciated that other work-holding fixtures can be employed in the collet in accordance with the character and shape of the tool to be held in grinding position.

Figure 8 illustrates use of the fixture for angle drilling of holes. In this instance, the fixture is mounted on the work table 66 of a drill press having a tool-carrying head 67 and the conventional type of adjusting means 68. An adapter 69, similar to the adapter 56 but having a single wide groove similar to the groove 58 therein, is mounted in the fixture and the work piece 71 is secured therein. In order to guide the drill 72, the body member 26 is provided with a pad 73 having a key-way 74 therein. (Figure 1) for aligned mounting of a bracket 76 by means of a clamping cap screw 77. The bracket 76 has at its upper end a drill bushing 78 positioned with reference to the work to guide the drill 72 in entering at the proper angle. The adapter 69, shown in Figure 8, is used also to hold the rectangular shanks of Carboloy tool bits during sharpening.

In Figure 9, a modified form of the work-holder or fixture is provided in which the work can be turned during operation thereon, and, for this purpose, the body member 26a is provided with an apertured boss 81 on one end of which an electric motor 82 is mounted. Journalled in the boss 81 in any suitable fashion is a worm 83 carried at the end of the shaft of the motor 82 and engaging a worm gear 84 carried by the collet holding quill 36a. With this type of fixture, the power driven quill 36a can be rotated during the grinding of an annular surface on a work piece held in the collet of the fixture.

Figures 10 and 11 illustrate a modified form of the invention in which the base plate 10a is in the form of a disc having a transverse key-way 91 across its rear face and adapted for mounting within a recessed work plate 92 carried by the shaft 93 of a lathe. The base plate 10a carries an upstanding bracket 95 provided with a laterally projecting annular boss 27a on which the body member 26 of the fixture is journalled in the manner described in connection with the forms of the invention shown in Figures 1 to 5. One or more keys 94 on the face plate 93a engage the keyway 91 and a plurality of micrometer adjusting screws 96 in the annular flange 97 of the adapter plate 92 enable accurate off-center

positioning of the axis of the collet of the fixture with respect to the axis of the lathe for the machining or grinding of eccentric surfaces or pins on a work piece. The upper and lower screws 96 have tapered ends to engage transverse grooves 98 and wedge the parts together.

With reference to Figure 3, it is to be noted that the collet-holding quill 36 is adapted to be removed from the boss 31 with a work piece clamped in the collet 36 without disturbing the relation of the work piece to the indexing collar 42. This is accomplished by turning the cap screw 38 until its point recedes from the groove 37, at which time the quill 36 can be withdrawn from the collar 31, the clamping nut 48 and the washer 49 being of smaller diameter than the internal diameter of the boss 31 to permit this withdrawal without disturbing the clamping of the work piece. This enables use of the work piece in connection, for example, with a drill press, or permits insertion of a second quill 36 with another work piece without disturbing the adjusted relation of the work piece in the first quill 36 to the indexing collar 42.

While I have shown and described preferred embodiments of the invention, it will be understood that the invention is capable of variation and modification from the forms shown so that its scope should be limited only by the scope of the claims appended hereto.

I claim:

1. A universal fixture for grinding and the like operations comprising an elongated base member having a surface for engagement with a support, said base member having an annular boss at one end thereof projecting beyond said surface and having its axis positioned in parallel relation to said surface, an index mark on said boss, a body member having a pair of apertured bosses with their axes positioned at right angles to each other, one of said apertured bosses being journaled about said annular boss of said base member and having angle graduations for cooperation with said index mark, said body member being positioned in outboard relation to said base member, means for releasably securing said body member with respect to said base member, a collet-holding quill journaled in the other of said bosses of said body member, said quill having an annular groove intermediate its ends, a clamping screw threaded in the other of said bosses and engaging said annular groove, a collet in said quill, annular clamping means axially aligned with said collet for securing said collet in said quill and for securing a workpiece in said collet, said clamping means having a diameter less than the inner diameter of said other of said bosses whereby when said clamping screw is withdrawn from engagement with said an-

nular groove, said quill and said collet are freely withdrawable from said other of said bosses, a second index mark on said other boss, an indexing collar journaled about said quill and having graduations for cooperation with said second index mark, and means for releasably securing said collar to said quill.

2. A universal fixture for grinding and the like operations comprising an elongated base member having a surface for engagement with a support, said base member having an annular boss at one end thereof projecting beyond said surface and having its axis positioned in parallel relation to said surface, an index mark on said boss, a body member having a pair of apertured bosses with their axes positioned at right angles to each other, one of said apertured bosses being journaled about said annular boss of said base member and having angle graduations for cooperation with said index mark, said body member being positioned in outboard relation to said base member, means for releasably securing said body member with respect to said base member, a collet-holding quill journaled in the other of said bosses of said body member, means for releasably securing said quill in the other of said bosses, said securing means being disengageable from said quill, a collet in said quill, and annular securing means axially aligned with said collet for attaching said collet to said quill and for securing a workpiece in said collet, said securing means being disposed within the internal diameter of said other of said bosses to permit bodily removal of said quill, said collet and the workpiece held thereby, a second index mark on said other boss, an indexing collar journaled about said quill and having graduations for cooperation with said second index mark, and means for releasably securing said collar to said quill.
